United States Patent Office.

CHARLES SPENCER, OF PHILADELPHIA, PENNSYLVANIA.

Design No. 3,398, dated March 2, 1869.

DESIGN FOR THE LEG OF A STOCKING.

The Schedule referred to in these Letters Patent and making part of the same.

To all whom it may concern:

Be it known that I, CHARLES SPENCER, of Philadelphia, county of Philadelphia, State of Pennsylvania, have originated a new Design for the Leg of a Stocking; and I do hereby declare that the accompanying drawing, and following explanation thereof, form a full, clear, and exact description of the said design.

In the drawing, the figure represents sufficient of the leg of a stocking to illustrate my design, which consists of stripes A and B, arranged longitudinally with the leg.

Irrespective of the colors employed in carrying out my design,

I claim the design for the leg of a stocking, substantially as described, and represented in and by the accompanying drawing.

In testimony whereof, I have signed my name to this specification, in the presence of two subscribing witnesses.

Witnesses:

JOHN WHITE,
H. SMITH.

CHAS. SPENCER.
